UNITED STATES PATENT OFFICE.

THEODORE J. WEBER, OF GRAND RAPIDS, MICHIGAN, AND ARCHIBALD S. B. LITTLE,
OF ST. LOUIS, MISSOURI.

MANUFACTURE AND DISTRIBUTION OF GAS.

980,889.

Specification of Letters Patent.

Patented Jan. 3, 1911.

Application filed May 2, 1910. Serial No. 558,979.

To all whom it may concern:

Be it known that we, THEODORE J. WEBER, a citizen of the United States, residing at Grand Rapids, in the county of Kent and State of Michigan, and ARCHIBALD S. B. LITTLE, a subject of the King of Great Britain, residing at St. Louis, State of Missouri, have invented certain new and useful Improvements in the Manufacture and Distribution of Gas, of which the following is a full, clear, and exact description, reference being had to the accompanying drawings, forming a part hereof.

Our invention has relation to improvements in the manufacture and distribution of gas; and it consists in the novel features more fully set forth in the specification and pointed out in the claims.

In the drawings, Figure 1 is a plan of a gas-plant showing our invention applied thereto, the building for the machinery and retorts being shown in section; Fig. 2 is an elevation of the main portion of the plant, parts in the rear being omitted; Fig. 3 is a broken elevation of the hydraulic main and vacuum tank or holder coupled thereto; and Fig. 4 is a cross section taken through the hydraulic main on the line 4—4 of Fig. 3.

The present invention is not restricted in its application to any particular gas, being applicable equally to ordinary illuminating gas made by the destructive distillation of coal, to water-gas, or producer gas, and in the drawings herein, the invention is shown in connection with both illuminating and water (or producer) gas.

Among the objects sought by the present system are (1) to insure a substantially constant and uniform pressure condition within the retorts (where retorts are employed as in the case of ordinary illuminating gas) such uniformity being brought about by establishing a substantially constant and uniform difference between the pressures in the dip-pipes discharging into the hydraulic main, and that of the gases above the liquid in the main; (2) to maintain this uniform (and constant) difference between the aforesaid pressures irrespective of the rapidity or rate (and volume) of evolution of gas from the retorts, said difference remaining practically unaffected whether a retort is operating on a fresh fuel charge, or whether such charge has been partially distilled; (3) to provide suitable means in the shape of a

vacuum-tank or receptacle having a fluctuating holder or bell for temporarily accommodating the variable quantities of gas evolved from the retorts, said vacuum-tank constituting the immediate source of supply of the gas traversing the system of cleaning machines ordinarily comprising in succession the condenser, washer, scrubber and purifier as well understood in the art; (4) to maintain in the system of cleaning machines ideal pressure conditions by means of an exhauster, or an exhauster and compressor combined, at the outlet or discharge end of said cleaning machines, the gas being drafted from the vacuum-tank through the machines into suitable storage or pressure tanks, and the exhauster-pump being operated at such speed as to take away approximately uniformly per hour the variable amount of gas made at different hours, and temporarily accumulated in the fluctuating vacuum-tank; (5) to so construct the vacuum-tank or fluctuating holder that irrespective of the volume of gas temporarily accumulated therein, the load exerted on the exhauster or pump shall be substantially constant thereby making the rate of flow of the gas through the cleaning machines constant, which rate of flow may be varied according as the consumption may vary; (6) to interpose suitable means between the cleaning machines and exhauster-pump for regulating the intensity of the draft exerted by the pump on the machines; (7) to dispense with the usual gas holder or gasometer and in lieu thereof force the gas into suitable pressure-tanks from which the gas may be conducted into any service pipe operating under any predetermined pressure; and (8) to provide further and other features of construction and arrangement the advantages of which will be fully apparent from a detailed description of the invention, which is as follows:—

Referring to the drawings, R, R, represent a bench of gas-retorts with the usual ascension pipes *a* terminating in the dip-pipes *d*, the discharge ends of which extend a suitable distance below the surface of the liquid condensed and precipitated in the hydraulic main *M*. These features of course, are well understood in the art and require no further description. Leading from the hydraulic main *M* is a foul-pipe or main *1* which discharges into the holder or fluctuat-

ing member 2, said member being in the form of a vessel open at the bottom and operating in a water seal in an outer tank 3, as usual in the ordinary form of gasometer or holder. In the present instance however, the member 2 is so counterweighted that the weights w thereof constantly exert an upward pull thereon, and thereby produce a partial vacuum in the holder above the surface of the water seal, said vacuum corresponding substantially to about a one-inch column of water. The weights w are suspended by cables or cords 4 passing over sheaves or pulleys 5 mounted on brackets 6 at the top of the tank 3. The holder 2 thereby becomes in effect a vacuum-tank, the degree of vacuum depending on the gravity of the weights w , the vacuum in the holder exerting a suction or draft on the foul main 1, and hence on the gases in the hydraulic main M above the liquid in said main. The degree of this draft or suction is regulated by the bench governor G, preferably on the order of that described in U. S. Letters Patent 937,828, dated October 26, 1909, and in practice the governor is so weighted as to produce a suction of one-tenth of an inch water column on the inlet side, the vacuum in the holder 2 being kept as near as possible to one inch water column. So that if the dip-pipes have their discharge ends submerged two-tenths of an inch below the level of the liquid in the hydraulic main, the suction of one-tenth inch (water column) exerted on the main will reduce the height of the liquid column in the discharge ends of the dip-pipes one-tenth of an inch below the surface or level of the liquid in the main, thereby reducing the total height of the column in the dip-pipe to one-tenth of an inch. If the dip of the dip-pipes be three-tenths of an inch, then the governor is so weighted as to exert a suction of two-tenths of an inch on the main, and thus again bring down the total height of the column in the dip-pipe to one-tenth of an inch. It follows therefore that the gases evolved from the retorts (or other source of gas supply) need depress or displace a liquid column of but one-tenth of an inch in order to escape from the dip-pipes and bubble through the liquid accumulating in the main. This liquid or tar is of course drawn off in the usual manner through a discharge or overflow pipe 6 as shown.

Leading from the vacuum tank or holder 2 is a conducting pipe 7 which carries the gas from the holder 2 to the first of the series of cleaning and purifying machines or equivalent apparatus, such apparatus ordinarily comprising a condenser C, a washer W, a scrubber S, and a purifier F, all well understood in the art, and requiring no detailed description here. Conducting the purified gas from the purifier is a pipe 8 in

the path of which is interposed a compensating tank and governor G' on the order of that of G previously referred to, and a gas-meter 9 of any approved type, the gas being withdrawn from the meter by a combined exhauster and compressor pump P which drives the gas into a primary pressure tank 10 where it is stored to a pressure of approximately seventy-five pounds to the square inch, whence it flows into a secondary pressure tank 11 where it is allowed to accumulate to a pressure of say thirty-five pounds, a convenient reducing valve or governor 12 being provided for the purpose between the two tanks. From the tank 11 the gas passes through a governor or reducing valve 13 when it enters the service main 14 at a pressure of approximately one pound or any pressure in fact, to which the governor may be set.

The operation of the invention and the theory of that operation may be described as follows:—Since the vacuum-tank or holder 2 exerts a constant draft on the foul main and on the hydraulic main, reducing the liquid column in the dip-pipes to approximately a constant and uniform head of one tenth inch, it follows that the resistance offered to the passage of the gas (coming from the retorts) is represented by the depression of this reduced column, which when overcome, allows the gas to freely bubble through the tarry and ammoniacal liquor constantly depositing in and constantly withdrawn from the hydraulic main. Now, a one-inch vacuum in the tank or holder 2 represents a certain elevation of said holder under the action of the counterweights, and as fast as this vacuum is formed it is instantly filled by the gas flowing into the holder past the governor G. As fast as the vacuum in the holder 2 is filled with gas, the weights w reassert themselves and lift the holder so as to create more vacuum which again fills with more gas, provided it is evolved in sufficient quantities from the retorts. If the evolution is greater (as with a fresh fuel charge) than could be accommodated with a given rise of the holder under the action of the weights w , then the latter will keep on dropping and continue to raise the holder for the accommodation of more gas; but at all stages a positive draft or suction would be exerted on the foul and hydraulic mains, the degree of which would be regulated to maintain the column in the dip-pipes at substantially one-tenth of an inch in height (and where the dip is two-tenths of an inch, the top of this depressed column would be one-tenth of an inch below the surface of the liquid in the hydraulic main). The suction, or exhausting action of the holder 2 therefore permits the holder to accommodate any volume of gas which may be evolved (from the retorts) be the same

great or small. If great, then the holder rises; if small, then it drops (owing to the abstraction of the gas therefrom by the exhauster pump P , and the resulting atmospheric pressure on the holder which acts in opposition to the weights w) so that it becomes a fluctuating holder, the fluctuations depending on the volume of gas temporarily accumulated therein. The holder 2 does not 5 serve therefore as a holder or gasometer proper, but as a mere temporary gas retainer taking care of the variable quantities of gas coming from the retorts; but irrespective of that quantity the conditions within the retorts 10 remain practically constant and uniform, by reason of the maintenance of a constant and uniform depression in the liquid column in the dip-pipe, a constancy assured partly by the governor G , and partly by the 15 constant abstraction of the gas from the vacuum-tank under the action of the exhauster pump P . For it must be obvious that were the pump P to stop, the gas might keep 20 on accumulating in the vacuum-tank 2 until the latter had been raised to its limit, after 25 which the gas evolved from the retorts would cease to have an outlet. In the operation of our system, the draft on the vacuum-tank should be as near uniform and constant as 30 possible. We of course, know the approximate resistance offered to its passage through the cleaning apparatus composed of the condenser, washer, scrubber and purifier respectively, and it becomes desirable that in 35 view of this resistance the governor G' be so set as to cause the gas to pass into the meter 9 at a constant, uniform and predetermined pressure on its way to the exhauster and compressor pump P . Naturally, the 40 rapidity and intensity of the abstraction of the gas from the holder or vacuum tank 2, through the cleaning and purifying apparatus must be commensurate with the rate of generation and evolution of the gas from the 45 retorts, but as to this, the governors may always be set to insure the required results. The positioning of the pump P beyond the purifier as against the prevailing method of interposing the pump between the condenser 50 and foul main has a decided advantage, because even where in the latter case the pump is provided with any well known form of governor-controlled steam or gas-valve to vary its speed to meet the conditions of variable 55 evolutions of gas, we secure a better result by a pump drafting or sucking the gas through the cleaners and purifier, than by the old method of forcing the gas through this same apparatus; and this is even true where the 60 rate of flow through the cleaners and purifier may, for one reason or another, vary. With our system however, this variation is negligible because the fluctuating holder or vacuum-tank 2 always maintains a constant 65 and sufficient supply of gas to be drafted

by the pump P ; and should this supply exceed the quantity discharged by the pump for any given speed of the latter, the pump may be increased in speed for the purpose. It is our aim however, to provide a vacuum-tank of sufficient capacity to serve as a receptacle for a sufficient quantity of gas as not to necessitate any material change from that already outlined, in the pressure conditions between the foul and hydraulic mains and the ascension and dip-pipes (and consequently the gas retorts). 70 75

It may be added in passing, that the presence of the governor G' prevents any material pulsations within the cleaning and purifying apparatus as a result of the reciprocations or rotations of the pump P , said governor likewise serving as a compensating tank which destroys such pulsations, the governor G' being on the order of 80 the governor G . So that the governor G' serves to maintain the proper conditions not only in the cleaning and purifying apparatus, but also in the meter 9 as the gas is passing onward to the pump P . By the 85 disposition of the vacuum-tank 2, governors G , G' , and pump P as here outlined we are therefore able to maintain the proper working and pressure conditions throughout the entire system, both as to pressures, rate, and 90 intensity of flow of the gas; and in so far as the retorts are concerned, we get a constant (and uniform) pressure condition within them without the need of a gas-pump or exhauster between the hydraulic main 95 and condenser. The pressure tanks 10 and 11 are of course, not indispensable to our system, but by virtue of the specific location of the exhauster and compressor pump P , they may be availed of, their immediate 100 connection to the pump making it possible 105 to use them for the purpose to which they are here put.

As was stated at the outset, the present system may be used with any gas; and in 110 Fig. 1 we show in a conventional way a supplemental plant for manufacturing water gas (or for that matter it might be producer gas) in which a pipe conducts the gas from the gasometer into the hydraulic main, where, by absorbing the proper and available hydrocarbons from the tarry liquid in the main, the gas becomes enriched and mixed with the retort gas already described. Referring therefore, again to the drawings, 115 15 represents a steam boiler, a steam pipe 16 leading therefrom to an engine 17 which operates a blower or fan 18 supplying the necessary air to the coke-charge of a gas-producer or furnace 19. Through the incandescent carbon in said furnace steam is 120 passed from the boiler through a pipe 20, the water gas thus formed being conducted past a well 21 (to remove suspended impurities) through a pipe 22 into the gasom- 125 130

eter or holder 23. A pipe 24 conducts the water-gas from the holder into the hydraulic main (dipping into the liquid therein) the enriched gas mingling with the retort gas, the combined gases being treated as already described. In lieu of water-gas, the furnace 19 may be used for making producer gas, and the holder 23 for storing the same, in which event the like treatment could be accorded the last named gas.

Features shown in the drawings, but not referred to, are well understood in the art and require no description here.

Having described our invention, what we claim is:

1. In combination with a hydraulic main, a dip-pipe leading thereinto from a suitable gas-retort, a vacuum-tank in communication with the main above the liquid therein and provided with a movable holder actuated to exert a suction on the main, thereby depressing the liquid column in the discharge end of the dip-pipe below the level of the liquid in the main.

2. In combination with a hydraulic main, a dip-pipe leading thereinto from a suitable gas retort, a vacuum tank in communication with the main above the liquid therein and provided with a fluctuating holder counterweighted to exert a constant suction on the main, and a governor interposed in the path of the gases between the main and holder, thereby causing a constant and uniform depression of the liquid column at the discharge end of the dip-pipe below the level of the liquid in the main.

3. In combination with a hydraulic main,

a dip-pipe leading thereinto from a suitable gas retort, a vacuum-tank in communication with the main above the liquid therein and provided with a fluctuating holder counterweighted to exert a constant suction on the main, an exhaust pump for removing the gas from the vacuum tank, and suitable gas cleaning and purifying apparatus interposed between the vacuum tank and exhaust pump.

4. In combination with a hydraulic main, a dip-pipe leading thereinto from a suitable gas retort, a vacuum-tank in communication with the main above the liquid therein and provided with a fluctuating holder counterweighted to exert a constant suction on the main, a governor interposed in the path of the gases between the main and holder thereby causing a constant and uniform depression of the liquid at the discharge end of the dip-pipe below the level of the liquid in the main, an exhaust pump for drawing the gases out of the vacuum tank, and a suitable series of cleaning and purifying apparatus interposed between the vacuum-tank and the pump.

In testimony whereof we affix our signatures, in presence of witnesses.
